W. Kendall,

Water Wheel

Patented Jan. 12, 1831.

Jan 12 1881

289.

William Kendall Fosfield Mass.

Letter Patent X 6336

The Schedule referred to in these Letters Patent, and making part of the same containing a description in the words of the said William Kendall himself of his improvement in the mode of applying water to Mill wheels.

To all persons to whom these presents shall come, William Kendall of Fosfield in the County of Worcester and State of Maine, Hillwright sends greeting. Be it known that William Kendall, have made a new and useful discovery or invention in the application of water whilst acting upon Mill wheels which he calls the Zephon principle, that is after the water has performed the full measure of its action upon the wheel by percolation, or rather reaction, the water impinging like a jet has the required velocity equal to that propagated under the same heads the effects of this velocity of the water is still continued by this invention to act upon the same wheel by causing its force to be expended in removing the atmosphere from the lower or opposite side of the blique buckets and openings of the wheel, which pressure never exceeds, yet always is equal to the weight or head of water of 33 1/3 feet, or fifteen pounds to the square inch; this pressure becomes proportionately diminished according to the head of water used; by causing the water from the wheel to jump off, between two plain surfaces, with a fixed space, a proper degree larger than the body of water in motion naturally occupy, this space becoming an increased as it extends from the wheel, and does not require to be extended further than to allow its outer and inner openings to be sufficient to discharge the quantity of water expended by the wheel at the rate of from two to six feet per second as the quantity of water may require; this discharge in all cases must be laid below the surface of the water that the water be prevented from entering within the wheel the draught of the

wheel

which it is to use a pump and will be better explained after explaining the common nature of science as it stands at the present time. Under wheels or water acting by its gravity they have the advantage of producing effects greater and greater, as we enlarge the wheel for holding & retaining all the water until its motion becomes clearly discernable, yet it is not in our power to obtain one third more in effect from them, than is obtained by following the judicious rules, directed by science, & as their effects are estimated at two thirds of the power applied, the requisite strength and expense is proportionally increased, if we rise beyond this diminishing line we increase the other in the same geometrical progression.

The next case is where one half the velocity is multiplied by three quarters of its greatest load, & water acting by percolation on undershot wheels which are variously made, and in these most perfect form. Their effects are rated at $\frac{1}{4}$ of the power applied, here from an application of your invention, by using thin buckets of about one third the width of the acting extension of water, and increasing the number in that ratio their effect become increased; a suggestion of this principle as applicable to steam boat wheels was published in 1810, & intending for that purpose it should be given the advantage in proportion at the back side of the buckets. But here I specify that from a reaction of water, not only from reaction that may arise from a weight of water above the wheel by placing it near the upper part of a confined reservoir, but from velocity or the force of percolation than applied, by my invention which I claim. Reaction wheels are those which move by reaction of the water, their effects have been estimated by the same ratio as undershot wheels; this principle of reaction of fluids was first noticed in Roman time, but only from one of their bridges suspended having an oblique issue the solitary Midland nation was given, it is the late Dr. Baskerville applied it to mechanical purposes, from an issue at the end of a hollow arm, and after this applied to a circular wheel to act under water by means of having a tube of lead by this the whole wheel can be made and many proofs of power will be obtained where no other wheel could be applied, yet this apparent

valuable principle mentioned only by himself is wholly abandoned in the late edition of his work alleging that they (the wheels) have not succeeded the cupolas introduced of them to. This was un-
desirable and owing to the want of a proper system to connect the
wheels they have generally made a much waste of water in a
short time after built a little use required, much of this early
waste of the difficulty in connecting the main wheel to the shaft, this
with the change of position from the center of the gunpowder, the
unwinding of the wheel in other parts, causing its wearing into
more way the space between it and the stream, making a hole wide
by every particle that is drawn within by the water, then this part
connected with in wheels of my construction, but the assurance that
the wheel will support a perfect circle and that the shining is
smaller and in that part where the velocity of the water is great and
is in the direction to make waste or let in the particles to cause
its wearing away.

From all reaction wheels the quantity of water which issues
from the wheel is increased with the velocity of the wheel, and also
the velocity of the water is increased when the motion of the wheel is
diminished by its load.

Your inventor pretences that he will be excused from making a
more particular investigation, by saying that in 1815, he gave the
common reaction wheel to present form of buckets by making them
thin of a sea shell, instead of spiral segments, this was an improve-
ment as there was less action of resistance against the back side of
the buckets, they being only lashed, sufficient to give a proper de-
flection the discharging water shortly after; this became under a
patent from a person under contract and, pretence never explains
the principle, neither has it ever been explained worth repeating here.
They discharge the water outward from the shaft the buckets run
between two iron, with the shaft connected to one, but the
wheel which I have so selected and applied to my invention
was buckets as it were at right angles with the frame which con-
tains

be thus. The water may come to rest upon it by pressure from the whole of the bank, but it is only by reaction that the wheel moves.

It is a wheel which I have constructed for use in making and permanency of its parts may represent in a glancing view, that which was formerly called a tub wheel except it has no arms, the buckets entering the shaft and are supported in the rim, they lie very flat and very thin, their edges which cut and leave the water, are made sharp by their obliquity, they scarf or lap over each other, and the space between them all is called the shear, or spaces of the wheel, they decline about the orifice inches to a foot of their width, for a wheel of four feet diameter with seven buckets their width becomes about 15 inches at the shaft and two feet at the rim, this rim then requires to be about two inches wide and deep so as to extend one inch below the buckets, and two inches above the piping of the edge bar of iron through which its thick edge rests against, and fair with the bucket as a cutter and being driven well into the shaft the other end bent down and supported under a hoop which is made like the rim and wheel, which leaves a concave form at its upper side, and is made flat at its bottom, it has a shaft for its support commonly of half the diameter of the wheel, when the said mortices are made small portions of the wood are left to support its shaft end, the buckets being slit to fit the same, if the buckets were wholly of iron, plate or cast iron made smooth it would be better although as it is requisite that the wheel should be always under water, it is not subject to decay still for high heads, the wheel should be made wholly of metal, with just proportion fair smooth, as they become very small, hereafter one of such wheels will be described. The next is the gyron, so much difficulty has attended this point in the common reaction wheel as to render one proportion to their use, and although the wheels of my construction have lost weight from their reduced size, still an improvement in the way of fastening is urgent, and that the wheel may be raised or lowered, adjusting it for the draught by the same. Therefore gyroscopes for high heads are made of wood and to be easily managed about the wheel, it

the end of any convenient length, say twelve feet and from four to six inches wide, not more than eight inches high. This stand is to be fitted with a thin taffety, piece of twine of its sides for its support. it is then supported by being blocked down at one of its corners, then weight being given to the cramp, so that it does not rise, its lower end at its sides resting against a perfect square hoop made of plate iron, about two inches wide, which is bolted, and secured in the shaft and bushings. The thickness of the above taffety piece, cutting them for convenience on the lowest and right side, with the said iron blocking on the same corner; now view ~~in~~ the judge standing in an open boat above the wheel. this mortise is cut obliquely and large enough to admit the judge readily after the weight of the shaft is removed from the said blocking, and for its security in using common bolts, a part of the wood is proportionally removed from each corner, and more allowed. Therefore for this judge to stand upon it conveniently, it is made about one and a half thick with a projecting edge to rest upon the wood, which is a flat or rather a platform, made so somewhat raised, and extends beyond the rim of the wheel forming the lower part of the draught, the centre of this platform to be filled for the boat as it hangs upon its edge, clear water surrounds its bottom. A $\frac{1}{2}$ boulder sink hole is made at one side of the centre of the box, and the wood is scraped away from its bottom, with a larger hole continued down through, that the water may rise. For the water is past it has circular concaves of the proportion of half an inch deep for five inches face. This creates a tremulous motion which causes party to inhale the water below in the surface. This system will not wholly apply unto flat or upright shafts and for wheels over two feet in diameter, offering too common fixtures for judges when they ride, and to observe the above principle, continuing to describe the wheel and fixtures, for applying the plain principle. The wheel is now supported to stand upon its four ~~legs~~ with the lower part of its rim so far above the platform as to give an opening between them equal to twice that of the opening of the wheel, in this way a very inclosed

caria, as for small vehicles with high heads (as may require more), the inside of the lower corner of the rim is conical, and rounded off between the hub and the lower part of the hub-hole, so as to about above the edge of the rim, this space between them, and the platform below the base of the wheel, the basal part of the platform below the hub-hole, the broad of the wheel, the space between the hub-hole and hub is about one-fifth more than the measure of that part of the opening above. This is some make-up part of the draught, for diminishing the draught beyond the wheel consisting of timber or other material circumscribing the wheel and extending with even thickness and level the cavity, for convenience about one foot, as for example, of the head and the broad is to make in timber; and the head to four feet diameter, with respect opening, that is to say 12-4 feet the space opposite under the rim, which rim is 10 feet in circumference, and the 4 feet 8 1/2-11 1/2, which divided by the rim 12 is -8 inches for its height above the hub-hole, and its outer discharge extending one foot beyond the wheel, and increases the opening at the charge half as much more, that is 2 feet, and the head 7 feet, and over half a score more still to be added for the air charging space, which is now -4 feet, and 4-2-1/4 or 1/2 inches long with the opening of the wheel; which having for effect head or 16 feet velocity throughout, then by 4x4=32, feet per second, or equal to a head ratio less than two inches last. This application, this extension of the draught may suffice for heads from 100 to 200 feet, or may easily be extended. That surely nothing is lost yet small wheels have more than simple, inconveniences from the same extent of the draught, in respect to the head lost, yet as the head can be varied, and as it is not for so many natural forces to direct the water outward, the draught might be made downward even to accumulate great part of its force within the same part lost. But every resistance from so natural a source, is a loss in the application. This application being able to demonstrate that if a confined space of 1000 feet square

is fitted under a head of water of 333 feet, and moves below the surface its gate then having the pressure 2183 lbs when shut, and if the gate is half opened it will then have the same pressure over the half of gate, that it had on the whole surface, whilst it was shut, for when the gate is half drawn the recession of the issuing water repels the incumbent water from the lower side and produces a recession there, and if this half gate was allowed to move onward through the penstock, with half the natural velocity of the water, (or 40 feet per second) which is the same velocity which is given by $\frac{1}{10}$ of the head 333 ft = $3\frac{1}{3}$ feet, or $3\frac{1}{3}$ feet, it would then have the pressure exerted upon it, equal to $\frac{1}{10}$ of that which it had before it moved, which is $\frac{1}{10}$ of 2183 lbs = 151.2 lbs, moving this with half the velocity of the water, whilst the opening remained is but the half of 2183 or 1143 lbs, and if this gate is so laid inclosing the part of the wheel, on which I apply this principle with the same effect. The above may suffice to show the reason why the wheel requires double resistance to stop its motion, than the whole amount of pressure removed by its opening, that is such half of the opening for the wheel, with this application produces equal effects to a that which was established for the common reaction wheel, or with the same opening, produces double effect, or hereafter explained, the water acts upon the wheel by its whole head, & whatever may be its velocity inciting it into the stream (or sounding the wheel) its motion should be the same, way which the wheel may move, as from the opening being directed to that side of the shaft to give this motion round the shaft, and if the wheel is within a penstock where the water descends to it, such fixtures as I principally should be applied to its sides to give this direction, this exactly prevents a whirlpool, which would otherwise destroy the action, and also has other protective effects for preventing waste of water outside of the rim as a protective stiffener is placed upon the curving timber and

and covering the rim of the wheel its inner edge comprising
therewith, and having this a wiper of wood nailed so as to
extend down to near the collar or beecholt. The wheel is sup-
posed to be turned off by its rotation in that part. The wheel
should however have a small diameter nearly sufficient to visit the
requisite quantity of water. There is no assurance that its small
surface and weight will with increased velocity at its contac-
ting, all tend to diminish friction, and the water acts upon
it with equal force, yet some increase its life. The buckets
become more flat for convenience, having one wheel of great
force, the diameter of another, with different openings, may
be found from the square of the diameter of the given wheel
or vice versa, as the proportion of their openings may be the qua-
re root of the product of the diameter of the required wheel, to apply
different powers with different heads. The quantity of water
or rather the power to be used, must be estimated by common
power, such as that of a millstone of four feet diameter, requiring
one horse to be constantly exerted at a point two feet from its center
when the velocity is 20 feet per second, then at 8²⁰ is 4000.0000
the is raised one foot per second by that power, and for two feet
it would be 8000 lbs, one foot high per sec. And the weight of
cubic foot of water is 62 lbs, which by the wheel head in feet
gives the pressure on one foot of surface, or opening removed,
and from this point, more or less, as the opening of the wheel may be,
to which add half a square more for the maximum load. This
being multiplied by half the velocity of the water per second in
feet, gives the effect, and in the comparison of the above
the velocity of the water per second divided by 8, gives the
square 1/8 of its head & the square root of its head $\times$ 5 is its
velocity per second in feet. Then if the wheel had a feet
head applied with 2 feet opening its effect would be calculated
as follows 1/8 1/8 a = 1/8 5, and a/8 and 1/8 5, the opening. The
product is to be on the millstone, and its weight of 4000
pounds

being 100 inches or 11 feet circumference of revolution per second on 43 ft per minute, or in other words the centrifugal pressure is equal to $93 \frac{1}{2}$ the farce every square foot of opening in the wheel, which multiplied by the head in feet, the product is the maximum load of the wheel, and this multiplied by half the velocity per second, gives the load or number of lbs, that can be raised one foot per second. Example if $33 \frac{1}{2}$ head, was applied to this wheel, then $93 \frac{1}{2}$ lbs. x by 2 = $197 \frac{1}{2}$ lbs by $33 \frac{1}{2}$ = 6500 lbs. the maximum pressure, at the centre of the buckets, which being $\frac{1}{4}$ of the velocity per second = 23 feet, gives 140750 lbs, that can be raised. This divided by 4000, gives near 36 millstones, or if divided by 300, it shows the horse power. And if it were required to construct a wheel with this head, to be equal to the power of one horse, to pull off, that is to say = 350 pounds, it = divided, and applied a circumference for this opening, from the last wheel, it would be $\frac{1}{4}$ that is = to 36 , the square root being $\frac{6}{4}$ of a foot or 6 inches, for the diameter of the wheel, therefore four buckets would be proper of thin plate, mounted on about 7 inches on the circle of the wheel, whereby are supported by a hoop made of plate about 2 inches wide and thick, its edge projecting above the buckets, about $\frac{3}{4}$ of an inch, this hoop should be turned fair, especially within to receive the edge of a, another cylinder hoop, to enter properly within, to near the buckets, for preventing waste of water, its opposite part is secured to the peristock, as the wheel is supposed to sit within one, and the shaft to extend through the sides of the same observing that the shaft may become 4 or 5 inches diameter, for the support of the wheel, and other parts of it, one inch, if the part to be connected are first coated with lead, may be soldered, and the corners formed to allow an easier transmission to prevent friction, the maximum load $173 \frac{1}{2}$ lbs, and revolutions 12 times per second, or 720 per minute, is too swift to attempt to gearing with common wheels, and the motion is generally swift, with this application, with this we should reduce the driving wheel to

like or larger inches diameter, it will often be difficult to gear from this, it may seem better to describe a new form of gear, which I have introduced for saving expense, and preventing friction by making them in logs with wide bearing. For the common wheel or gear requires 23 parts or joints, for setting in each log, having two rim parts which cannot well apply to regular movement. Therefore the spur wheel is made wholly from large timbers, which is formed into sectional parts of the circle of the wheel say 13, 15, 20 logs, pieces to have alike size and number of logs, on the end of each sectional piece. These pieces are made wider as to give a great width to the cog; and also about two inches to act as a rim, when turned off for meeting the other wheel, that it may not jar from the pitch circle. A proportional part of them extend into the shaft as arms having a shoulder at their under edges which end is also slit by the saw, that it may be strained to fill the mortise. The other parts are merely dovetailed upon these; and the wheel is supported by the iron hoop on each side; these hoops are let into the wood several inches from the outer edge of the wheel, and secured by a spanner key. 316 logs with one inch space may be had with 18 pieces; that is 18 logs on each, or if 24 pieces of logs you will need for one gear observe the same principle, but here the gain of the wood becomes the same way with that of the shaft, and the wheel is secured to arms which are movable when necessary and required to be set upon the same wheel, whilst the other allows of adding a proportionate piece between the parts or joints to enlarge its diameter for the same purpose. The substance of the hoop may vary with the size of these wheels as from piece eight to one inch square, that it may bear a heavy strain, when small wheels as when the driving or wheel is made of iron. The iron cog should be cut with the thickness of the wood over in its bearing wheel, the design to increase the number and surface of the cog by making

which makes shorter which is done by turning off and — now
allowing the air into a space between them & the air is now for
moving the word.

They have endeavoured to explain the principle, and how
to use this invention where an additional artificial pressure
is applied to the wheel increasing its effects by motion; which
is call the Supple principle, where, the force of percussion
operates as well as gravity is applied to repel the atmospheric
pressure, which balance among themselves, when applied
to small wheels; also the wheel and parts for applying the
same according to their specification.
